PRINT-HANDLING DEVICE

Louis Phillip Martinek, Cleveland, Ohio

Application August 30, 1945, Serial No. 613,564

4 Claims. (Cl. 95—100)

1

The invention relates to improvements in print-handling devices and particularly to articles of this character for lifting wet photographic prints or enlargements from acid, alkaline, and poisonous solutions during course of development.

The purposes of the invention are to provide a simple device for the purposes stated which may be economically manufactured and conveniently and reliably operated, is non-injurious to the prints handled, will protect the solutions which are used for the development and also protect the hands of the operator.

The improved print-handling device is a wire formation and two forms thereof are shown in the accompanying drawing and described in detail hereinafter.

In the embodiments of the improved print-handling device shown in the accompanying drawing both forms of the wire formation are shown as comprising two complementary half-formations which are secured together, one of the half-formations forming an inner part of a paddle portion of the device and also a part of the handle, and the other half-formation forming an outer part of the paddle portion and also a part of the handle, the handle portion of the inner part also being bent to form a trigger-like finger grip and, in one of the two forms of the device shown, being bent also to provide a spring-like print-retaining finger.

The annexed drawing and the following description set forth in detail certain means illustrating the instant improvements in print-handling devices, such disclosed means constituting, however, only two of the various forms in which the principle of the invention may be embodied.

In said annexed drawing:

Figure 1 is a perspective view of one form of print-handling device illustrating the instant improvements, the view also showing how a print is snared and lifted by the paddle portion of the device; and

Figure 2 is a perspective view of a second form of said improved print-handling device.

As above stated, the improved print-handling device is a wire formation and the wire, which is non-corrodible by the solutions utilized for developing photographic prints, is bent so as to provide certain necessary parts of the complete device, such as a paddle serving as a scoop, a handle, and a trigger-like finger grip. The wire is also bent to form notched portions which engage the peripheral rim of the solution receptacle and prevent the device from slipping into the receptacle. The wire which is bent to produce one form of the

2

device, viz., that shown in Figure 1, is also bent to form a spring-like print-retaining finger. Both forms of the device can snare and lift a print by its paddle portion and the form shown in Figure 1 can also perform these functions by means of the spring-like print-retaining finger.

The forms of the device shown in the accompanying drawing are made from two wires which are, broadly speaking, an inner wire and an outer wire. The two wires are bent to form an elliptical-appearing paddle portion and the inner wire is continued to provide a part of the handle including the trigger-like finger grip, and the outer wire is continued to form a major part of the handle and is also formed with non-slipping notches for holding the device on the peripheral rim of the solution tank. In the form of the device shown in Figure 1 the inner wire is also continued to form a print-retaining spring-like finger.

The paddle portions of the two forms of the device are similar and the inner wire section thereof consists of two opposed members curved to form a comparatively wide elliptical-shaped opening therebetween, and the outer wire section consists also of two opposed members curved to form an elliptical-shaped opening therebetween, the width of the opening between each outer member and the adjacent inner member being relatively narrow as compared with the width of the opening between the opposed inner members.

Insofar as the snaring of a print by the paddle portion of the device is concerned, so as to lift the print from a solution receptacle, both forms of the device have similar paddle portions and the wires of the latter are passed by a corner of the print in the solution so as to engage the wet print in the manner clearly illustrated in Figure 1, i.e., one of the outer paddle wires is passed under the print corner and another paddle wire is passed over said print corner whereby the wet print clings to the paddle, as illustrated in Figure 1, and can be lifted from the solution.

Oftentimes, it is desirable to lift the print from the solution in a manner other than that just described relative to the use of the paddle wires therefor and, for this purpose, supplemental means are provided, such as shown in Figure 1, these means being similar, in an improved wire formation, to those shown in my Patent No. 2,381,765, and consisting of a spring-like finger which is formed at its free end with a print-engaging tong, which free finger end is normally slightly spaced from the device area where the paddle portion merges in curved formation with

the handle portion so that the paddle can be slipped under the edge of the print until a portion of the print lies under the tong finger when the spring finger can be compressed by the operator's thumb to cause the tong to grip the print against the adjacent portion of the device.

Referring to the annexed drawing, and particularly referring first to the form of the device shown in Figure 1, the wire formation has an elliptical-shaped skeletonized paddle portion 1 consisting of two opposed outer inwardly concave wire sections 9 and 10 which are the ends of the wire 3 of which this part of the paddle is comprised and have overlapping terminals 9¹ and 10¹. The central portion of another wire 4 is bent to form wire sections 14 and 15 which are opposed and are inwardly concave and are disposed interiorly of the respective wire sections 9 and 10, being respectively spaced from the latter so as to form elongated comparatively narrow curved openings 17 therebetween, the spacing between the inner wire sections 14 and 15 being relatively wide as compared with the width of the openings 17 so as to form an elliptical-shaped comparatively wide opening 18.

The joint or nose 16 of the wire sections 14 and 15 engages the terminal 10¹ of the outer wire section 10 and this nose 16 and the wire terminals 9¹ and 10¹ are flattened out into a chisel-like formation 19 and secured together by a weld 20.

The two outer wire sections 9 and 10 are continued rearwardly in spaced parallel relation to form a part 6¹ of the handle portion 6, having an upper and inner looped end 12, the wire of this part 6¹ of the handle member 6 being bent to form a plurality of downwardly-extending notches 7 substantially midway its length.

The inner wire sections 14 and 15 are continued rearwardly in close parallel relation, and interiorly of and somewhat above the handle wire parts of the outer wire sections to a point slightly rearwardly of the notches 7 where they are bent to form a downwardly projecting trigger-like finger grip 8. These rearwardly extended parts of the inner wire sections 14 and 15 also form a part 6² of the handle portion 6 of the device. From the finger grip 8 the inner wire sections 14 and 15 are upwardly extended through the loop 12 formed by the handle wire parts of the outer wire sections 9 and 10, and then bent forwardly and continued above and longitudinally of the handle 6 to a point adjacent and above the center of the inner end of the paddle portion 1 where they are bent sharply downwardly and terminate slightly above this rear end of the paddle portion 1. These last-mentioned portions of the inner wire sections 14 and 15 are the two ends thereof and these ends are passed through a section 11 of rubber tube which secures them together, the terminal portions 14¹ and 15¹ being slightly bent upwardly into a hook formation. The forwardly-extending lengths of the wire sections 14 and 15, above the handle 6, form a spring-like finger 5 which can be depressed by the operator's thumb to cause the tube section 11 to engage a print which has been underpassed by the paddle 1 and is rested thereon, whereby the print can be lifted from the solution. Intermediate its ends the spring-like finger 5 is bent downwardly and upwardly to form a second trigger-like finger 13 which serves, if desired, to depress the tube section 11 and cause it to engage and hold a print rested on the paddle 1.

The form of the device shown in Figure 2 also 75

has a skeletonized paddle portion 2 comprised of opposed inwardly concave outer wire sections 21 and 22 of a wire 3¹ and opposed inwardly concave inner wire sections 23 and 24 of a wire 4¹ forming elongated comparatively narrow curved openings 25 and an elliptical-shaped comparatively wide central opening 26. The terminals 21¹ and 22¹ of the outer wire sections 21 and 22 overlap and are formed into a chisel-like end 27 with the central nose 28 of the inner wires 23 and 24, the whole being secured together by a weld 29, similarly to the structure shown in Figure 1. The outer paddle wire sections 21 and 22 are continued rearwardly in spaced relation to form the handle portion 30, having the inner and upper looped end 34, an intermediate part of which handle portion 30 is bent to form the non-slipping notches 31. Also, similarly to the formation shown in Figure 1, the inner paddle wire sections 23 and 24 are continued rearwardly in close parallel relation, and within and slightly above the wire sections of the handle portion 30, to a point beyond the notches 31 to form a handle portion 35, and thence downwardly to form the trigger-like finger 32. However, the wire forming the inner part of the structure shown in Figure 2 ends with the formation of the trigger-like finger 32, this finger 32 being formed of the ends of the inner wire which are secured together by a weld 33. In other words, the form of the device shown in Figure 2 is designed for snaring the wet print and lifting it out of the solution tank by the use of the spaced paddle wire sections 21, 22, 23 and 24 only, and is not made with the additional print-snaring and lifting means provided by the spring-like finger 5 forming part of the device shown in Figure 1.

The two outer elongated comparatively narrow openings 25 and the central comparatively wide elliptical opening 26 of the skeletonized paddle 2, Figure 2, afford considerable latitude for the snaring and lifting of prints of different sizes and contours and positioned differently in the solution tank relative to the position of the operator who is manipulating the print-handling device. Likewise, the openings 17 and 18 of the form of the device shown in Figure 1 provide considerable manipulative latitude inasmuch as the skeletonized paddle portions of both the forms of device, Figures 1 and 2, are similar.

The advantages of the improved device, insofar as protection of the solutions and the operator are concerned, are especially important.

5 The wire of which the improved device is made is non-corrodible by the chemicals utilized, does not absorb the chemicals similarly to the human hand, and can be more easily cleaned. The solutions are kept chemically pure, thus lasting longer and resulting in better development, which increases production at a decrease in cost.

The manipulation of prints by human hands damages valuable negatives and produces stain marks and finger prints thereon. Such manipulation also produces stains on paper due to handling with warm hands, especially in warm weather. The instant improved print-handling device eliminates these difficulties.

70 The use of the improved device also speeds up production for another reason, and that is, when one operator is performing the work, the necessary frequent washing and drying of hands between developing and printing results in considerable loss of time.

A safety feature incident to the use of the

improved device is also very important. Often-times, the putting of the operator's hands into the various solutions results in blood poisoning from metol, acids, etc. This is particularly true when the operator's hands are chapped or cracked by reason of frequent washing thereof and repeated immersion in the solutions.

What I claim is:

1. A print-handling device comprising a wire formation consisting of two wires, each of which is bent to form a forward symmetrical paddle part of spaced wire sections, said wire sections of one wire lying exteriorly of and spaced from the wire sections of the other wire, all of said wire sections forming a skeletonized paddle, the inner wire sections being continued rearwardly to form a handle part and then bent downwardly and upwardly to form a trigger-like finger grip and thence continued forwardly in substantially parallel relation with and slightly above said handle part to form a spring-like finger, which finger terminates in a print-gripping tong adjacent the rear end of the skeletonized paddle, the ends of said inner wire sections being secured together in said tong area, the outer wire sections also being continued rearwardly to form a handle part adjacent the handle part of the inner wire sections, the handle part of the outer wire sections terminating in an extended looped rear end thereof, the inner and outer wire sections being secured together in a chisel-like formation at the forward end of the skeletonized paddle.

2. A print-handling device comprising a wire formation consisting of two wires, each of which is bent to form a forward symmetrical paddle part of spaced wire sections, said wire sections of one wire lying exteriorly of and spaced from the wire sections of the other wire, all of said wire sections forming a skeletonized paddle, the inner wire sections being continued rearwardly to form a handle part and then bent downwardly and upwardly to form a trigger-like finger grip and thence continued forwardly above said handle part to form a spring-like finger, the finger intermediate its ends being bent downwardly and upwardly to form a second trigger-like finger grip, means enclosing the forward terminals of the inner wire sections and forming a print-gripping tong adjacent the rear end of the skeletonized paddle, the outer wire sections also being continued rearwardly to form a handle part adjacent the handle part of the inner wire sections, the handle part of the outer wire sections terminating in an extended looped rear end thereof, the inner and outer wire sections being secured together in a

chisel-like formation at the forward end of the skeletonized paddle.

3. A print-handling device comprising a wire formation consisting of two wires, each of which is bent to form an end symmetrical paddle part of spaced wire sections, all of said wire sections being relatively laterally disposed and lying substantially in the same plane to form a skeletonized paddle, one wire being continued rearwardly from the paddle to form a handle part and then bent downwardly to form a projecting trigger-like finger grip, the other wire also being continued rearwardly from the paddle to form a handle part closely-grouped with the first-mentioned handle part and thence continued rearwardly thereof to form a looped handle part, the several wire sections being secured together in a chisel-like formation at the forward end of the skeletonized paddle.
4. A print-handling device comprising a wire formation consisting of inner and outer wires, each of which is bent to form an end symmetrical paddle part of spaced wire sections, all of said wire sections being relatively laterally disposed and lying substantially in the same plane to form a skeletonized paddle, the inner wire being continued rearwardly from its paddle sections to form a handle part and then bent downwardly to form a projecting trigger-like finger grip, the outer wire also being continued rearwardly from its paddle sections to form a handle part closely adjacent the first-mentioned handle part and thence continued rearwardly to form a closed looped handle terminal, the inner and outer wire sections being secured together in a chisel-like formation at the forward end of the skeletonized paddle.
